ATTORNEYS.

UNITED STATES PATENT OFFICE.

JOHN SANDLES, OF HINSDALE, ILLINOIS.

WASHING-MACHINE.

SPECIFICATION forming part of Letters Patent No. 228,685, dated June 8, 1880.

Application filed November 20, 1879.

To all whom it may concern:

Be it known that I, JOHN SANDLES, of Hinsdale, in the county of Du Page and State of Illinois, have invented a new and Improved 5 Clothes-Washer, of which the following is a specification.

Figure 1 is a side elevation of the device, partly in section. Fig. 2 is a plan of the same. Fig. 3 is a plan of the under side of the plunger and attached cups.

Similar letters of reference indicate corresponding parts.

This invention relates to that class of devices in which clothes are cleansed by the action of cup-plungers.

The invention consists of a circular plunger made to nearly fit the tub, and provided on its under side with several circular cups, that are so fastened to it that they can revolve in 20 a horizontal plane.

In the drawings, A represents a standard, and B an adjustable jaw secured to the said standard A with links C. The standard A and jaw B are set on the edge of the tub D, (indicated in dotted lines, Fig. 1,) and firmly held thereto by the thumb-screw E.

F is a lever having a slot, a, in one end, and it is secured to the standard A by a bolt or screw, b, that passes through the said slot 30 a, the length of the said slot a determining the adjustability of the said lever F on the bolt or screw b.

The upper end of the plunger-rod G is connected with the lever F at any convenient 35 point by the pin c, that passes through the said lever F and through the plates H, between which the said rod G is fastened, as shown. The lower end of this rod G is cen-

trally fastened to the cross-bar O of the plunger I, while the brace-rods K K, that extend 40 from the cross-bar O of the plunger I to either side of the rod G, hold the said plunger I in position.

To the under side of the plunger I several smooth-rimmed cups, L L, are so fixed by bolts 45 or pins d d that they (the cups L L) can revolve in a horizontal plane, each on its bolt or pin d, independently of the others.

The plunger I is designed to be of nearly the diameter of the tub to which it may be attached, so that a minimum amount of water 50 shall splash or flow over the edges of the plunger when the said plunger I is in operation.

Each cup L is formed without a seam, of tin or other metal, to insure durability and in 55 order that it may be rendered air-tight when in the water of the tub, so that it may the better force the suds through the clothes. The pin d may be provided with a packing-ring between its head and the cup.

The device is operated by moving the lever F up and down.

Having thus described my invention, I claim as new and desire to secure by Letters Patent—

As an improved article of manufacture, a clothes-washer constructed as herein described, and consisting of the circular plunger I, provided with a series of seamless revolving cups, L L, rod G, slotted lever F, and standard and 65 jaw A B, as herein shown.

JOHN SANDLES.
